UNITED STATES PATENT OFFICE.

JOSEPH W. TROHA, OF CLEVELAND, OHIO.

VALVE-RESEATING TOOL.

Application filed May 11, 1927. Serial No. 190,580.

My invention relates to valve reseating tools.

The object of my invention is to provide a valve reseating tool of this general character by which the seats of faucets, valves and the like can be accurately resurfaced, trued and renewed, so that washers will seat properly. The parts are adjustable and reversible. The centering element being constructed to fit over or into the different sizes of valve openings into which the valve trimmings are mounted when the valve is in use.

In the accompanying drawings forming a part of this specification and in which like numerals designate like parts throughout the same:—

Figure 1 is a sectional view of the tool, showing same applied to a faucet, and showing parts broken away to show its interior construction.

Figure 2 is a side view.

Figure 3 is a sectional view of the tool showing the centering element reversed on the feeding device, adapted to faucets of this type, a portion broken away to show the threads on the interior of the valve opening.

Figure 4 is a cross section of the tool-stem shown in Figure 1 on the line A—A.

Figure 5 is a cross section of the tool-stem shown in Figure 2 on the line B—B.

Figure 6 is a cross section of the tool-stem shown in Figure 3 on the line C—C.

Figure 7 is a side view of the tool-stem clamping means.

Figure 8 is a side view of the feeding device.

Figure 9 is a bottom view of the cutter shown on the tool-stem in Figure 1.

Figure 10 is a bottom view of the cutter shown on the tool-stem in Figure 2.

The parts may be identified by reference numerals with which they are designated upon the drawings, and are characterized individually as now set forth.

The faucet 1 shown in Figure 1 shows the standard construction in which the seat of the faucet 2 is an integral part of the body. The faucet or valve seat may have a flat face as shown adapting it to flat washers, or a conical face adapting it to a conical washer, (not shown but understood in the art.)

3 an opening in the valve body into which the valve trimmings are mounted when the valve is in use, the valve body may be provided with outside threads as at 4, or inside

threads as at 4^c adapted to take the valve cap, (valve cap not shown but understood in the art.)

The rotating means 5 is secured to the tool-stem at its upper end. The tool-stem 6 is provided with a longitudinal groove 7, adapted to engage the end of the locking means 17. The lower end of the tool-stem is provided with a reduced integral section 8, threaded to engage the threaded bore 11 in the cutter 9. The cutter may have a flat face as shown in Figure 1, or a conical face as shown in Figure 2 designated 9^b.

The cutter is provided with a plurality of cutting edges as shown in Figure 9 at 10:10; or as 10'—10' in Figure 10.

The centering element 26 is of conical configuration provided with external threads 27, and internal threads 28, and an internal stop face 29, and an external stop face 30, and axial threaded bore 31.

The feeding device 18 having formed integrally therewith at its upper end a socket 20, and a socket wall 21, and provided with an axial smooth bore 12 to engage the tool-stem, and also provided with a threaded exterior 19 adapted to engage the axial threaded bore 31 in the centering element. The lock ring 24 is internally screw-threaded 80 registering with the threaded exterior of the feeding device, the flat face 25 of which coacts with the stop face 30, when the tool is used as shown in Figure 1, and the stop face 29 when the tool is used as shown in Figure 3. The lock ring is adapted to lock the feeding device against movement in the centering element.

The clamping means 13 has an integral reduced portion 15, intermediate this portion an annular groove 16, and an axial smooth aperture 12 to engage the tool-stem, a threaded bore 14 at right angles to the axial smooth aperture is adapted to secure the locking means 17. The clamping means 100 is rotatably mounted in the socket of the feeding device, and secured therein by the terminal ends of the securing pins 23: 23, that pass through the perforations 22: 22 in the socket wall 21. These pins have a tight fit in the socket wall, but a loose fit in the annular groove so as not to interfere with the independent rotation of the tool-stem clamping means in the socket, or the independent rotation of the feeding device on 105 the clamping means. The tool-stem 6^b is round. The tool-stem 6^c has a flat face as

shown at 32 in Figures 3 and 6, adapted to accommodate the end of the tool-stem locking means.

The tool-stem being mounted in the tool-stem clamping means and feeding device, is slidably mounted in the clamping means when the grooved or flat sided tool-stem is used, and is slidably and rotatably mounted when the round tool-stem is used, and is 10 slidably and rotatably mounted in the feeding device in all cases. It is therefore evident that when the reseating tool is secured to the faucet to be reseated and the cutter is brought in contact with the valve seat and 15 locked in the clamping means, the tool-stem with its cutter can be carried up and down by turning the feeding device.

The tool-stem can be operated independently by the locking means alone, the necessary downward pressure being manually applied to the rotating means on the upper end of the tool-stem in the renewing movements, by simply alternating the locking and releasing of the tool-stem as desired, 25 because the tool-stem being locked in the clamping means can not ride up from the valve seat, thus always giving a preferably true valve seat, irrespective of the feeding method used in the combination.

30 The operation of the device is obvious.

The tool is secured to the faucet or valve, the cutter brought into contact with the valve seat, the tool-stem locked in the clamping device, the handle revolved, the feeding 35 means is turned slightly downward thus pressure is applied to the cutter, the operation is repeated until desired results are obtained.

The construction of the tool can be partly 40 of steel and partly some other metal, or all of steel or some other metal, the construction itself can be made such as to attain the required strength without special reference to the materials used.

45 While in the foregoing there has been illustrated in the drawings and described in the specification such combinations and arrangement of elements as constitute the preferred construction or embodiment of this 50 invention, it is nevertheless desired to emphasize the fact that interpretation of the invention should only be conclusive when made in the light of the subjoined claims.

What I claim is:—

55 1. In a valve reseating tool of the class described, the combination of a conical centering element externally and internally threaded having an axial threaded bore and also internal and external stop faces, said centering element being adapted to be attached to a valve-casing, a feeding device in threaded engagement with the centering element and a lock ring, and provided with an axial smooth bore and also with an integral socket wall at its upper end adapted

to hold a clamping means, said socket wall also having perforations adapted to retain securing pins, a tool-stem clamping means having an axial smooth aperture, also an integral reduced portion with an annular 70 intermediate groove and a threaded bore at right angles to the axial smooth aperture for securing a tool-stem locking means, said clamping means being rotatably mounted in the socket and secured therein by the terminal ends of the securing pins which pass through the socket wall and engage in the annular intermediate groove, a lock ring screw-threadedly engaging the feeding device and co-acting with the external stop face to limit movement, a tool-stem with a longitudinal slot therein slidably mounted in the clamping means and slidably and rotatably mounted in the feeding device, adapted at 75 its lower end to threadedly engage a cutter having a plurality of cutting edges and at its upper end a rotating means to operate the said tool-stem with its cutter, and a lock screw in the clamping means to engage the longitudinal slot in the tool-stem to lock said 80 tool-stem in the clamping means so as to hold the cutter against the valve seat.

2. In a valve reseating tool of the class described, the combination of a conical centering element internally threaded having 85 an axial threaded bore and also internal and external stop faces, said centering element being adapted to be attached to a valve-casing, a feeding device in threaded engagement with the centering element and a lock ring, and provided with an axial smooth bore and also with an integral socket wall at its upper end adapted to hold a clamping means, said socket wall also having perforations adapted to retain securing pins, a tool-stem clamping means having an axial smooth aperture, also an integral reduced portion with an annular intermediate groove and a threaded bore at right angles to the axial 90 smooth aperture for securing the tool-stem locking means, said clamping means being rotatably mounted in the socket and secured therein by the terminal ends of the securing pins which pass through the socket wall and engage the annular intermediate groove, a lock ring screw-threadedly engaging the feeding device and co-acting with the external stop face to limit movement, a tool 95 stem with a longitudinal slot therein slidably mounted in the clamping means and slidably and rotatably mounted in the feeding device adapted at its lower end to threadedly engage a cutter having a plurality of cutting edges and at its upper end a rotating means to operate the said tool-stem with its cutter, and a lock-screw in the clamping means to engage the longitudinal slot in the tool-stem to lock said tool-stem 100 in the clamping means so as to hold the cutter against the valve seat.

3. In a valve reseating tool of the class described, the combination of a conical centering element internally threaded having an axial threaded bore and also an internal stop face, said centering element being adapted to be attached to a valve-casing, a feeding device in threaded engagement with the centering element and provided with an axial smooth bore and also with an integral socket wall at its upper end adapted to hold a clamping means, said socket wall also having perforations adapted to retain securing pins, a tool-stem clamping means having an axial smooth aperture, also an integral reduced portion with an annular intermediate groove and a threaded bore at right angles to the axial aperture for securing a tool-stem locking means, said clamping means being rotatably mounted in the socket and secured therein by the terminal ends of the securing pins which pass through the socket wall and engage in the annular intermediate groove, a tool-stem with a longitudinal slot therein slidably mounted in the clamping means and slidably and rotatably mounted in the feeding device, adapted at its lower end to threadedly engage a cutter having a plurality of cutting edges and at its upper end a rotating means to operate the tool-stem with a cutter and a lock screw in the clamping means to engage the slot in the tool-stem to lock said tool-stem in the clamping means so as to hold the cutter against the valve seat.
4. In a valve reseating tool of the class described, the combination of a conical centering element externally threaded having an axial threaded bore and also an internal stop face, said centering element being adapted to be attached to a valve-casing, a feeding device, in threaded engagement with the centering element and a lock ring, and provided with an axial smooth bore and also with an integral socket wall at its upper end adapted to hold a clamping means, said socket wall also having perforations adapted to retain securing pins, a tool-stem clamping means having an axial smooth aperture, also an integral reduced portion with an annular intermediate groove and a threaded bore at right angles to the axial aperture for securing a tool-stem locking means, said clamping means being rotatably mounted in the socket and secured therein by the terminal ends of the securing pins which pass through the socket wall and engage in the annular intermediate groove, a lock ring screw-threadedly engaging the feeding device and co-acting with the internal stop face to limit movement, a tool-stem with a longitudinal slot therein slidably mounted in the clamping means and slidably and rotatably mounted in the feeding device, adapted at its lower end to threadedly engage a cutter having a plurality of cutting edges and at its upper end a rotating means to operate the tool-stem with its cutter, and a locking means in the clamping means to engage the slot in the tool-stem to lock said tool-stem in the clamping means so as to hold the cutter against the valve seat.
5. In a valve reseating tool of the class described, the combination of a conical centering element externally threaded having an axial threaded bore, said centering element being adapted to be attached to a valve-casing, a feeding device in threaded engagement with the centering element and provided with an axial bore and also with an integral socket wall at its upper end adapted to hold a clamping means, said socket wall also having perforations adapted to retain securing pins, a tool-stem clamping means having an axial smooth aperture, also an integral reduced portion with an annular intermediate groove and a threaded bore at right angles to the axial aperture for securing a tool-stem locking means, said clamping means being rotatably mounted in the socket and secured therein by the terminal ends of the securing pins which pass through the socket wall and engage in the annular intermediate groove, a tool-stem with a longitudinal slot therein slidably mounted in the clamping means and slidably and rotatably mounted in the feeding device adapted at its lower end to threadedly engage a cutter having a plurality of cutting edges and at its upper end a rotating means to operate the tool-stem with its cutter, and a lock-screw in the clamping means to engage the slot in the tool-stem to lock said tool stem in the clamping means so as to hold the cutter against the valve seat.
6. In a valve reseating tool of the class described, the combination of a conical centering element externally and internally threaded having an axial threaded bore and also internal and external stop faces, said centering element being adapted to be attached to a valve-casing, a feeding device in threaded engagement with the centering element and a lock ring, and provided with an axial bore and also with an integral socket wall at its upper end adapted to hold a clamping means, said socket wall also having perforations adapted to retain securing pins, a tool-stem clamping means having an axial smooth aperture, also an integral reduced portion with an annular intermediate groove and a threaded bore at right angles to the axial aperture for securing a tool-stem locking means, said clamping means being rotatably mounted in the socket and secured therein by the terminal ends of the securing pins which pass through the socket wall and engage in the annular intermediate groove, a lock ring screw-threadedly engaging the feeding device and co-acting with the internal stop face to limit movement, a tool-stem with a longitudinal slot therein slidably mounted in the clamping means and slidably and rotatably mounted in the feeding device, adapted at its lower end to threadedly engage a cutter having a plurality of cutting edges and at its upper end a rotating means to operate the tool-stem with its cutter, and a locking means in the clamping means to engage the slot in the tool-stem to lock said tool-stem in the clamping means so as to hold the cutter against the valve seat.

stem slidably and rotatably mounted in the clamping means and feeding device, adapted at its lower end to threadedly engage a cutter having a plurality of cutting edges and at its upper end a rotating means to operate the said tool-stem with its cutter, and a lock screw in the clamping means to engage the tool-stem to lock said tool-stem in the clamping means so as to hold the cutter against the valve seat.

7. In a valve reseating tool of the class described, the combination of a conical centering element externally and internally threaded having an axial threaded bore and also internal and external stop faces, said centering element being adapted to be attached to a valve-casing, a feeding device in threaded engagement with the centering element and a lock ring, and provided with an axial bore and also with an integral socket wall at its upper end adapted to hold a clamping means, said socket wall also having perforations adapted to retain securing

pins, a tool-stem clamping means having an axial smooth aperture, also an integral reduced portion with an annular intermediate groove and a threaded bore for securing a tool-stem locking means, said clamping means being rotatably mounted in the socket and secured therein by the terminal ends of the securing pins which pass through the socket wall and engage in the annular intermediate groove, a lock ring screw-threadedly engaging the feeding device and coacting with the internal stop face to limit movement, a tool-stem slidably and rotatably mounted in the clamping means and feeding device, adapted at its lower end to threadedly engage a cutter having a plurality of cutting edges and at its upper end a rotating means to operate the said tool-stem with its cutter, and a locking device in the clamping means to lock the tool-stem in the clamping means so as to hold the cutter against the valve seat.

JOSEPH W. TROHA.
